UNITED STATES PATENT OFFICE.

MICHAEL TRUHAN, OF PHILADELPHIA, PENNSYLVANIA.

ADJUSTABLE PATTERN FOR COATS.

No. 890,472.

Specification of Letters Patent.

Patented June 9, 1908.

Application filed April 16, 1900. Serial No. 13,049.

To all whom it may concern:

Be it known that I, MICHAEL TRUHAN, a citizen of the United States, residing in Philadelphia, Pennsylvania, have invented certain 5 Improvements in Adjustable Patterns for Coats, of which the following is a specification.

The object of my invention is to construct an adjustable coat pattern of a simple character, whose manipulations can be readily comprehended and whose range of adjustment is sufficient to provide for the entire range of sizes likely to be met with in ordinary work. This object I attain in the manner hereinafter set forth, reference being had to the accompanying drawings, in which—

Figure 1, is a view representing the various parts of a coat pattern constructed in accordance with my invention and intended 20 for the production of a coat known as a cut-away; Fig. 2, represents the parts of my improved pattern designed for the production of a sack coat.

The pattern for a cutaway coat constructed in accordance with my invention is shown 25 in Fig. 1 and comprises the foregoing parts, namely, the front body 1, the side body 2, the skirt 3, the back 4, and the tail 5, usually constituting part of the back.

30 The pattern for the front body 1 has a central vertical bar composed of sections 8, 9, 10, 11 and 12, the front bar composed of sections 13, 14, 15, 16, 17 and 18, a back bar composed of sections 19, 20, 21 and 22, a neck 35 portion composed of sections 23, 24, 25 and 26, a shoulder portion composed of sections 27 and 28, an arm portion composed of sections 29, 30, 31 and 32, a waist bar composed of sections 33, 34 and 35, a bottom bar composed of sections 36, 37, 38, 39 and 40, and transverse bars at the neck and breast, the neck bar being composed of sections 41, 42 and 43 and the breast bar being composed of sections 44 and 45.

45 The side body pattern 2 comprises a front bar composed of sections 46, 47 and 48, a rear bar composed of sections 49, 50 and 51, with upper curved portion composed of sections 52 and 53, an armhole portion composed of sections 54 and 55, a bottom bar composed of sections 56 and 57 and upper and lower transverse bars, the upper bar being composed of sections 58 and 59 and the lower bar comprising sections 60 and 61.

55 The back pattern 4 comprises the vertical bar consisting of sections 62, 63, 64 and 65, a

curved side-body bar consisting of sections 66, 67, 68 and 69, an armhole portion 70, a yoke bar consisting of sections 71 and 72, a neck bar comprising sections 73 and 74, and 60 upper, intermediate and lower transverse bars, the upper bar comprising sections 75 and 76, the intermediate bar comprising sections 77 and 78, and the lower bar comprising sections 79 and 80.

65 The lower ends of the front and back bars of the back pattern are joined to the top bar of the tail pattern 5, said top bar being composed of sections 81 and 82 from which depend the front and back bars of the tail pattern, the front bar comprising sections 83, 84 and 85, and the back bar comprising sections 86, 87 and 88, these two bars being connected at the bottom by a bar comprising sections 89 and 90.

75 The skirt pattern 3 comprises a top bar made up of sections 91, 92, 93, 94, 95 and 96, a front bar composed of sections 97, 98, 99 and 100, a back bar composed of sections 101, 102 and 103, a bottom bar composed of sections 104, 105 and 106 and a vertical bar extending from the junction of the front and bottom bars of the skirt to a point about midway of the top bar of the same and comprising sections 107, 108 and 109.

80 In the sack coat pattern shown in Fig. 2, the side body portion is omitted and the front body and skirt are formed in one piece, a single transverse bar in the skirt composed of sections 165, 166 and 167 taking the place 90 of the bottom bar of the body and the top bar of the skirt in the pattern as shown in Fig. 1. In this case also there is a transverse bar in the tail portion of the back of the coat, said bar being composed of sections 168 and 169. 95 but otherwise the sections comprising the pattern are substantially similar to the correspondingly numbered sections of the pattern shown in Fig. 1.

100 The sections of the various bars of the different patterns overlap each other and are slotted longitudinally for the reception of securing devices whereby the overlapping sections are held together and secured in position after adjustment and said sections are 105 graduated so as to provide for a regulated adjustment. For ordinary cases but three measurements will be necessary, namely, that for the breast, that for the waist, and the measurement from the back to the waist, 110 the adjustments of the various other parts being to graduations corresponding to these

measurements except where peculiarities of figure require special adjustments of different parts to accommodate them.

I claim:

- 5 A pattern for the front body of a coat comprising front, rear and intermediate vertical bars, neck, shoulder and armhole bars and transverse shoulder, breast, waist and bottom bars, all of said bars being made in sections adjustable one upon the other within the area defined by the periphery of the pattern so that none of said bars can project
- 10

beyond said periphery, said intermediate vertical bar being rigidly connected to the transverse breast and waist bars where it crosses the same, substantially as described.

In testimony whereof I have signed my name to this specification, in the presence of two subscribing witnesses.

MICHAEL TRUHAN.
